UNITED STATES PATENT OFFICE

HOWARD D. COLMAN, OF ROCKFORD, ILLINOIS, ASSIGNOR TO BARBER-COLMAN COMPANY, OF ROCKFORD, ILLINOIS, A CORPORATION OF ILLINOIS

MACHINE FOR PRODUCING A CONNECTED SERIES OF HEDDLES

Application filed July 16, 1928. Serial No. 293,059.

This invention has special, although perhaps not exclusive, reference to heddles of the sort which are used in multiple-harness looms, as, for example, the form of heddle known in the trade as the Philadelphia steel heddle. The production of a machine for automatically drawing warp threads in the desired order through such heddles contained in a large number of harnesses involves the problem of selecting the heddle eyes singly and successively in the sequence determined by the pattern to be woven. In order to facilitate the selection of the heddles, I have conceived the idea of connecting the eyes of the heddles contained within a given harness or heddle frame by means of a series of chain stitches so that the whole series may be pulled along to bring successive eyes into or toward the position where they are to receive the warp threads. The present invention relates to a machine for producing such a connected series of heddles.

In the accompanying drawings:

Figure 1 is a fragmental front elevation of a machine embodying the features of this invention.

Fig. 2 is a plan view of the machine with certain parts broken away.

Fig. 3 is a horizontal sectional view in the plane of line 3—3 of Fig. 1.

Fig. 4 is a fragmental front elevation of the machine.

Fig. 5 is a vertical sectional view taken in the plane of line 5—5 of Fig. 1.

Fig. 5^a is a fragmental front view of the work plate.

Fig. 5^b is a fragmental plan section showing the presser foot, feed bar, looper and needle, the view being taken in the plane of line 5^a—5^a of Fig. 6.

Fig. 6 is a fragmental perspective view showing the vertically movable member 120 in the operation of positioning a heddle for engagement by the finger 135.

Fig. 7 is a fragmental perspective view showing the member 120 in its lowermost position and showing the finger 135 as having engaged the heddle.

Fig. 8 is a horizontal sectional view taken in the plane of line 8—8 of Fig. 5.

Fig. 9 is a sectional view in the plane of line 9—9 of Fig. 1.

Fig. 10 is an enlarged fragmental view of a connected series of heddles.

While the invention may be employed in connection with heddles of various forms, the present embodiment in the invention is especially designed to operate upon the form of heddle shown in Figs. 4, 5 and 10 and there designated A. Said heddle consists of a thin strip of steel having at either end an elongated opening B by means of which the heddle may be slidably mounted in a heddle frame. Intermediate its ends the heddle is provided with an eye C which stands at a slight angle to the plane of the body of the heddle. Just below the upper opening B and just above the lower opening B the heddle is provided with offset portions D, as described in my application Serial No. 692,645, filed February 14, 1924.

The machine herein shown is especially adapted to handle heddle frames of the kind disclosed in my application Serial No. 744,543, filed October 20, 1924 (now Patent No. 1,686,073, dated October 2, 1928). Such a frame comprises wooden top and bottom frame bars 1 and 2 connected at their ends by metallic bars 3. Mounted in and supported by the end bars 3 are the heddle-supporting bars 4 upon which the heddles A are slidably mounted in single file by means of their eyes B. Means is provided to support the bars 4 intermediate their ends, said means

comprising guide bars 5 (Fig. 4), one for each of the harness bars 1 and 2. The guide bars 5 are of approximately the same length as the bars 1 and 2. On each of the guide bars 5 is mounted a slide 9 (Fig. 4) comprising a depending portion 9^a having an opening 9^b through which the adjacent heddle bar 4 extends slidably. The slides 9 serve to hold the bars 4 in proper position with relation to the bars 1 and 2 when the heddle frame is in the loom, but said slides are freely movable substantially the full length of the heddle frame and thus interpose no obstacles to the compacting or sliding of the heddles along the bars 4 when the heddle frame is in the machine herein disclosed. The portion 9^a is suf-

ficiently thin so as to occupy the space between two heddles formed by the offsets D, and hence does not interfere with the operation of the heddle-selecting means herein-after described.

5 Any suitable means may be employed to support the heddle frame. The specific character of the heddle-frame supporting means will depend in part upon whether the heddle frame is traversed past stationary mechanism 10 for operating upon the heddles, or whether the heddle frame is stationary and is traversed by the operating mechanism. While the invention comprehends both arrangements, the 15 present drawings illustrate means generally similar to that disclosed in said application Serial No. 692,645 for supporting the heddle frame for movement past a stationary operating mechanism. There being a number of 20 screw heads projecting from the lower edge of the bar 2, the heddle frame is preferably set in a channel or shoe 10 (Fig. 5), said channel having recesses to receive the screw heads. The shoe 10 is arranged to slide in a guideway 11 (Figs. 2 and 5). The heddle frame is held in upright position in any preferred 25 manner, as, for example, by means which form a guideway through which the upper portions of the heddles pass.

30 Referring to Fig. 3, 12 is a guide plate fixed in the framework of the machine at the rear of the heddle frame and extending horizontally a short distance below the upper series 35 of offsets D. 13 (Figs. 3 and 4) are bars forming part of the stationary framework of the machine, said bars having attached to their lower ends a bar 14. The bars 13 and 14 are spaced away from the guide plate 12 sufficiently to allow a heddle frame to pass therebetween. A guide plate 15 is mounted on the 40 bar 14 parallel with and in the horizontal plane of the guide plate 12 (see Fig. 5) and is adjustable into and out of position to lie close to the heddles. In the plate 15 are inclined slots 15^a through which headed screws 15^b extend. After being manually adjusted 45 with reference to the guide plate 12 to form a guideway through which the heddles may travel, the plate 15 is fixed in adjusted position by tightening the middle screw 15^b. It will be understood that when a heddle frame 50 is to be placed in or withdrawn from the machine, the guide plate 12 is moved forward into position to clear the end bars 3 of the heddle frame.

55 Any suitable means may be employed to keep the heddles compacted together in the guideway formed between the plates 12 and 15 with the leading heddle pressed against a 60 selecting mechanism. Herein I have shown a slide 16 (Fig. 3) mounted in a guideway 17 (Fig. 5) provided in the framework of the machine, said guideway extending parallel with the guideway formed between the plates 65 12 and 15. To the slide 16 is pivoted at 18

an arm 19 having a vertically extending bar 19^a carrying three presser fingers 19^b (Figs. 1 and 4) arranged to bear against the rear-most heddle adjacent to the offsets D and at a point above the eye C. The operative position of the presser fingers is determined by contact of the stop portion 20 (Fig. 3) of the arm 19 with the slide 16. Any preferred means may be used to urge the slide 16 in the direction to press the fingers 19^b against the 70 heddles. Herein is shown a weight 21 (Fig. 1) which is connected to the slide 16 by means of a flexible connection 22, said connection extending over a guide sheave 23. A notch 23^a in the plate 12 is adapted to receive the bar 19^a and hold the slide 16 against movement by the weight 21, the heddle-compacting means being then out of the way when a heddle frame is to be placed in the machine.

75 While the heddle selecting and positioning mechanism may partake of various forms, the construction herein shown is like that disclosed in said application Serial No. 692,645. It comprises four arms 24, 25, 26 and 27 (Figs. 1, 4 and 5) arranged to swing into and out of engagement with the heddles. The arms 24 and 27 operate in front of the series of heddles, the arms 25 and 26 being arranged to operate behind the heddles. The lower end 80 of the arm 24 is formed to provide a finger 28 (Fig. 3) adapted to serve as an abutment against which the heddles are compacted by the presser fingers 19^b.

85 The lower end of the arm 27 (Fig. 6) is 90 provided with a finger 34 arranged to operate beneath the guide plates 12 and 15. The end of the finger 34 is made pointed to enter the space between a selected heddle and the next succeeding heddle. On the finger 34 is an inclined or cam surface 35 to crowd the selected heddle to the right and thus separate the upper end of said heddle from the remaining unselected heddles.

95 For a description of the construction and mode of operation of the arms 24, 25, 26 and 27, reference may be had to said application Serial No. 692,645. These arms are rocked in proper succession by means including a cam shaft 46 (Fig. 1). The cam shaft 46 is driven 100 by means of a helical gear 90 fixed on said shaft and meshing with a similar gear 91 carried by a vertical shaft 92. On the lower end of the shaft 92 is a spiral gear 93 that meshes with a similar gear 94 on a drive shaft 95.

105 Any desired means may be employed to move the heddle frame to the right as the heddles are being operated upon. I have herein shown for this purpose a rack bar 96 (Figs. 2 and 5) which is mounted in a guideway 97. To the left-hand end of the rack bar 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

101. Said lever is pivoted in the machine frame at 102. The other arm of the lever 101 is connected by means of a rod 103 to an eccentric stud on the inner end of a rock shaft 104. The forward end of said rock shaft carries a crank 105 by means of which the lever 101 may be swung to place the pinion 99 in and out of mesh with the rack bar 96.

10 The pinion 99 is rotated by means of a cam 106 (Fig. 4) fixed on the shaft 46. A 10 roller 107 on a bell crank 108 which is pivoted at 109 is held in contact with the cam 106 by a spring 110. The other arm of the bell crank 108 is connected by means of a link 111 to a crank arm 112 (Fig. 1) which is pivoted on the shaft 100. The crank arm 112 carries a pawl 113 that engages the teeth of a ratchet wheel 114 fixed on the shaft 100.

20 The heddle eyes C are kept in alignment by means of a needle-like rod 115 (Figs. 1, 3 and 4), the left-hand end of which is detachably secured to a bracket 116 forming a part of the machine frame.

25 The selector mechanism consisting of the arms 24, 25, 26 and 27 operates upon the upper ends of the heddles and serves to advance the upper ends of the heddles singly and successively from the series of unselected heddles. As the cam surface 35 (Fig. 6) moves 30 the upper end of a selected heddle to the right away from the unselected heddles, the lower end of said heddle lags. In order to continue the separation initiated by the selector mechanism 24, 25, 26 and 27 to the point where the sewing mechanism operates, 35 I provide an arm 120 which is mounted to slide up and down on a vertically positioned rocker bar 121. The pivots of the rocker bar are indicated at 122 and 123. In the free 40 end of the arm 120 is a wedge-shaped point 124 (Fig. 6), and to the right of said point is a notch 125. After the cam 35 has forced the upper end of a selected heddle away from the unselected heddles, the arm 120 is swung 45 to push the point 124 between the selected heddle and the foremost unselected heddle, the selected heddle being thus placed in the notch 125.

50 The means for swinging the arm 120 into and out of engagement with a selected heddle comprises an arm 126 (Figs. 6 and 9) fixed to the pivot 123 and having a roller that is held against a cam 127 on the shaft 92 by means of a spring 128.

55 After the arm 120 has been swung into engagement with a selected heddle, it is moved downwardly to place the heddle in approximately vertical position. The means for vertically reciprocating the arm 120 comprises a crank arm 129 (Fig. 1) fixed to the shaft 95 and connected by means of a rod 130 to a crosshead 131 which is mounted in a guide 132 fixed in the machine frame. A connecting rod 133 is pivoted to the crosshead 131 at its lower end and is connected at

its upper end to the arm 120 by means of a ball-and-socket joint 134 (Fig. 4).

60 Means is provided for accurately positioning the heddle eye for engagement by the feed bar of the sewing mechanism. This means comprises an arm 135 (Fig. 7) having two fingers 136 and 137 located in position to engage a heddle above and below and relatively close to the heddle eye. The end of the upper finger 136 is notched to engage 70 the heddle, the walls of the notch being inclined or flaring so as to locate the heddle accurately in position. The arm 135 is pivoted at 138 to an arm 139 which is fixed upon a vertical rock shaft 140 journaled in the 80 machine frame. To the lower end of the shaft 140 is fixed an arm 141 (Figs. 4 and 9) carrying a roller that bears against a cam 142 on the shaft 92. A spring 143 holds said roller against the cam. Reverting to Fig. 7, 85 a spring 144 tends to hold the arm 135 against an adjustable stop 145 carried by the arm 139. To the arm 139 is fixed a finger 146 (Fig. 8) which acts to prevent any but the selected heddle from entering the 90 notch in the finger 136.

95 Various forms of sewing mechanism may be employed, but that herein shown is generally similar to the Willcox & Gibbs single-thread chain-stitch machine, Type 500, manufactured under the Willcox & Noble Patent No. 276,113, the Willcox Patent No. 398,300 and the Norton Patent No. 525,043. A work plate 150 (Figs. 4, 5^a, 7 and 8) is stationarily supported in the machine frame rearwardly of the series of heddles. In the upper edge of the work plate is a notch 151 to afford clearance for the positioning finger 136. When in the position shown in Figs. 7 and 8, the lower finger 137 holds the portion of the heddle just below the eye C pressed against the work plate 150. There are two horizontal rows of square teeth 152 on the work plate 150, the teeth in each row being spaced apart just sufficiently to receive a heddle close to 100 the eye C. The spaces between the teeth are marked 153 in Fig. 5^a, there being eight such spaces in each row, although it may be noted that the exact number is not material. As shown in said view, the two rows of teeth 152 are spaced apart sufficiently to receive a 105 row of eyes C. 154 is an opening in the work plate through which the needle N is reciprocated.

110 The means for advancing heddle eyes singly and successively into operative relation with the needle and for moving sewed heddles away from the needle comprises a feed bar 155 (Fig. 8) and a presser foot 156 located at opposite sides of the work plate 150. The 115 needle opening in the presser foot is indicated at 156^a in Fig. 8. The presser foot is secured to a presser bar 157 which is slidably supported in the machine frame and is urged toward the work plate 150 by a spring 158. The 120

presser foot is of sufficient length to bear upon the heddle eyes C from a point shortly before the heddles are acted upon by the arms 24, 25 and 26, until after they have been stitched together. The bar 115 which holds the eyes C in alignment until the heddles reach the selector mechanism 24, 25 and 26 extends to a point just under the toe of the presser foot 156 and thus serves to guide the eyes C of the heddles under the presser foot.

The feed bar 155 comprises two parallel horizontally arranged bars 159 which are slidably mounted in slots 160 (Fig. 5^a) in the work plate 150. On the forward edges of the bars 159 are square teeth 161 like the teeth 152 and spaced similarly to said teeth. The rows of teeth 161 are at opposite sides of the presser foot 156. The spaces between the teeth 161 are designated 161^a (Fig. 6). The number of pairs of vertically aligned spaces 161^a corresponds to the number of pairs of vertically aligned spaces 153. As shown in Fig. 8, the bars 159 are long enough to operate upon at least three heddles at a time with three vacant spaces 153 between successive heddles. As indicated in Fig. 10, the needle N, the feed bar 155 and the looper L go through four cycles of movements per heddle. The movements of the feed bar 155 are similar to those in the Willcox & Gibbs machine. Assuming the feed bar 155 to be in its right-hand position, it is moved rearwardly until the teeth 161 no longer project beyond the forward face of the work plate 150; is then moved to the left a distance equal to the distance between the centers of two adjacent teeth 161, thus placing a pair of vertically aligned spaces 161^a directly behind a heddle engaged by the fingers 136 and 137; is then moved forward into engagement with said heddle and with any preceding heddles lying in the spaces 153, the forward movement being sufficient to carry the eyes C of said heddles forward of the vertical plane of the ends of the teeth 152, the arm 139 and the presser foot 156 yielding to accommodate such movement; is then moved to the right a distance equal to the distance between two adjacent teeth 161, the arm 135 swinging on its pivot 138 to allow such movement, and is then moved rearwardly to allow the fingers 136 and 137 and the presser foot 156 to press the heddles into the spaces 153. In this manner the heddle eyes C are advanced from one space 153 to the next, the operation of the needle, the feed bar and the looper being so timed with reference to the selecting mechanism 24, 25, 26 and 27 and the positioning arm 120 that four stitches S are formed per heddle, adjacent heddle eyes being thus connected together by a series of intervening chain stitches, as shown in Fig. 10. Each side of each heddle eye is enclosed within a stitch. Three stitches intervene between adjacent heddles.

It may be desirable to make a series several inches long of stitches after the last heddle has passed the needle. While heddles are passing through the sewing mechanism, the travel of the heddles suffices to pull the stitches out of the needle opening 154, but when the sewing mechanism is not operating on heddles it is necessary to have means to pull the series of stitches along to the right so as to prevent stitches from accumulating in the needle opening 154. I therefore attach to the feed bar 155 a block 162 (Figs. 5^b and 7) having two rectangular teeth 163. The block 162 is arranged to reciprocate in a rectangular opening 164 located midway between the slots 160 and to the right of the needle opening 154. The presser foot 156 comprises a yieldable section 165 located opposite the block 162, the section 165 being urged toward the block 162 by a spring 166. Being located in the horizontal plane in which the stitches are traveling, the teeth 163 press the stitches against the presser-foot section 165 and pull the stitches step-by-step to the right.

The teeth 163 are so located with reference to the spaces 161^a as successively to enter the heddle eye, thus serving to supplement the action of the teeth 161 in engaging and moving the heddles to the right. The presser foot is provided with the yieldable section 165 in order that it may accommodate itself to distorted heddles.

The looper L herein shown is like the one illustrated in Figs. 1 to 4, inclusive of the Borton Patent No. 525,043. It is rotated and the feed bar 155 reciprocated by means including a vertical shaft 166 (Fig. 5) bearing at its lower end a sprocket wheel 167 (Figs. 5 and 9).

The bar 168 (Fig. 5) that carries the needle N is reciprocated by means of a lever 169 which is pivoted at 170. The lower arm of the lever 169 is connected by means of a pitman 171 to an eccentric (not shown) on a vertical shaft 172. Fixed to the lower end of the shaft 172 is a sprocket wheel 173. A chain 174 (Fig. 9) extends around the sprocket wheels 167 and 173 and a sprocket wheel 175 fixed on the shaft 92. 176 is a slack-take-up idler. The thread tension 177 (Fig. 5) is like the one shown in the Gorton Patent No. 397,640 and is operated by means of a rod 178 engaging an eccentric (not shown) on the shaft 172. The spool of thread is supported on the spindle 179 (Figs. 1 and 2).

If desired, means may be provided to stop the machine in the event that operation of the arms 25 and 26 be interfered with, as by engagement with a defective or improperly positioned heddle. Such a means is fully disclosed in my application Serial No. 692,645. The same means is also shown herein, although not in detail. Instead of shifting a belt, as in the before mentioned appli-

cation, the safety stop mechanism is herein shown as arranged to open a switch 180 (Fig. 2) in the circuit of the motor (not shown) which drives the machine.

5 The operation may be summarized as follows:

After a heddle frame has been removed from the machine, the pinion 99 (Fig. 2) is lifted from the rack bar 96 by means of the 10 crank 105. The selector arms 24 and 27 are pulled forward, as explained in my application Serial No. 692,645, and the right hand end of the next heddle frame is passed between the forward arms 24 and 27 and the 15 rear arms 25 and 26. The lower edge of the heddle frame is set in the shoe 10 (Fig. 5). The heddle frame is then slid to the left until the right hand end of the frame is immediately to the right of the arms 24, 25, 26 and 27. 20 As the heddle frame slides to the left, it engages the finger 98 (Fig. 2) and thus moves the rack bar 96 also to the left. The heddles are then slid to the right on the bars 4 until the foremost heddle to the right is 25 in contact with the abutment 28 (Fig. 3). The guide plate 15 (Fig. 3) is then moved back close to the heddles. The bar 19^a (Fig. 3) is then withdrawn from the detent notch 28^a, and positioned so that the fingers 19^b 30 (Fig. 1) bear against the rearmost heddle, the weight 21 serving to compact the heddles against the abutment 28. The pinion 99 is then returned into mesh with the rack bar 96, and power communicated to the drive 35 shaft 95 (Fig. 1).

As the arm 27 (Fig. 6) sets off each heddle successively from the unselected heddles, the arm 120 swings into engagement with the heddle thus set off, and then moves downwardly to place the heddle in approximately vertical position. As the arm 120 completes its downward stroke, the arm 139 swings toward the rear to press the heddle against the work plate 150 immediately to the left of the teeth 152 which are farthest to the left. The pressure of the notched finger 136 and the square-end finger 137 causes the eye to lie flat against the work plate. The toothed bars 159 then advance to receive the heddle eye in the pair of vertically alined spaces 161^a which is farthest to the left, and to move the heddle eye forward beyond the vertical plane of the teeth 152. The bars 159 then move to the right to carry the heddle eye into position in front of the pair of vertically alined spaces 153 which is farthest to the left. The bars 159 then move back to deposit the heddle eye in said pair of spaces 153. The heddle eye is thus advanced step-by-step to 50 and past the needle. After the last heddle has passed the needle, the machine is continued in operation until a series of stitches several inches long has been formed, after which the heddle frame is removed and transported to the warp-drawing machine.

It will be understood by reference to Fig. 10 that the stitches, engaging as they do both sides of the eye, serve as a means of controlling the eye in the positioning of the latter, that the stitches between the heddles connect successive heddles together at approximately equal distances apart, and that the heddles may be disconnected by unraveling the stitches.

I claim as my invention:

1. The combination of chain-stitch-forming means including a work plate, a sewing needle and a looper, said work plate having a series of heddle-receiving spaces therein, and a feed member reciprocable longitudinally and transversely to advance a heddle from one space to the next and thus to and past the needle.

2. The combination of stitch-forming means, means for causing relative movement between the stitch-forming means and a rigid heddle frame containing a series of heddles slidably mounted in said frame, means for selecting heddles singly and successively from the series, and means for feeding selected heddles past the stitch-forming means.

3. The combination of stitch-forming means, means for causing relative movement between the stitch-forming means and a rigid heddle frame containing a series of heddles mounted to slide in said frame, and means for causing relative movement between the series of heddles and the stitch-forming means to bring successive heddles into operative relation to the stitch-forming means.

4. The combination of means for stitching the middle portions of heddles together, means for selecting heddles from a group of heddles, said selecting means operating upon the ends of the heddles, and means for bringing the middle portions of selected heddles into operative relation to the stitch-forming means, the third-mentioned means including means movable longitudinally of a selected heddle from a point near the selecting means to a point near the stitching means.

5. The combination of means for supporting a bar on which a series of Philadelphia steel heddles is strung, means for separating heddles singly and successively from the series and moving the separated heddles along the bar, means for fastening together the selected heddles by their eyes, and means for feeding selected heddles past the fastening means.

6. The combination of means for selecting a heddle from a series of unselected Philadelphia steel heddles suspended in single file, means for fastening heddles together, means for feeding heddles from one end of the series past the fastening means, and means for transferring heddles from the selecting means to the feeding means.

7. In a machine for sewing Philadelphia steel heddles together, the combination of means for selecting a heddle from a series of unselected heddles from one end of the series, means for sewing heddles together by a series of chain stitches, means for feeding heddles past the sewing means, and means for transferring heddles from the selecting means to the feeding means, said transferring means and feeding means acting to space heddles apart so that at least one stitch intervenes between successive heddles. 12. The combination of chain stitch forming means including a work plate, a sewing needle and a looper, said work plate having a series of heddle-receiving spaces therein, a feed member reciprocable longitudinally and transversely to advance a heddle from one space to the next and thus to and past the needle, and means for delivering heddles singly and successively to said feed member on nonconsecutive advancing movements of the latter, whereby the heddles are spaced apart with at least one stitch intervening. 70
8. The combination of means for supporting a bar on which a series of heddles is strung, a bar extending through the eyes of the heddles, means for selecting a heddle from the series, means for sewing heddle eyes together, means including a reciprocatory feed bar and a yieldable presser foot for feeding heddle eyes past the sewing means, the second mentioned bar extending close to the presser foot, and means for transferring heddles from the selecting means to the feeding means. 13. The combination of means for supporting a bar on which a series of heddles is strung, a bar extending through the eyes of the heddles, chain stitch-forming means including a work plate, a sewing needle and a looper, said work plate having a series of heddle-receiving spaces therein, a feed member reciprocable longitudinally and transversely to advance a heddle from one space to the next and thus to and past the needle, a yieldable presser foot, said feed member and presser foot being at opposite sides of the work plate, the second mentioned bar extending close to said presser foot, and means for delivering heddles singly and successively to said feed member on non-consecutive advancing movements of the latter, whereby the heddles are spaced apart with at least one stitch intervening. 80
9. The combination of means for selecting a heddle from a group of unselected heddles, means for sewing heddles together, means for feeding heddles past the sewing means, the selecting means and the sewing means operating upon separated portions of the heddles, means movable longitudinally of a selected heddle for moving toward the sewing means the portion of the heddle which is to be sewed, and yieldable means to receive the heddle from said longitudinally movable member and cooperating with said feeding means to control the heddle. 14. The combination of chain stitch-forming means including a work plate, a sewing needle and a looper, said work plate having a series of heddle-eye-receiving spaces therein, a feed member reciprocable longitudinally and transversely to advance a heddle eye from one space to the next and thus to and past the needle, a yieldable presser foot, said presser foot and said feed member being located at opposite sides of the work plate, and means for delivering heddle eyes singly and successively to said feed member on non-consecutive advancing movements of the latter, whereby the heddle eyes are spaced apart with at least one stitch intervening. 90
10. The combination of means for selecting a heddle from a group of unselected heddles, means for sewing heddles together, means for feeding heddles past the sewing means, said feeding means including a reciprocatory feed bar and a yieldable presser foot, the heddles moving between said feed bar and the presser foot, the selecting means and the sewing means operating upon separated portions of the heddles, means movable longitudinally of a selected heddle for moving toward the sewing means the portion of the heddle which is to be sewed, and two yieldable fingers to receive the heddle from said longitudinally movable means and cooperating with said feeding means to control the heddle, said fingers engaging the heddle at opposite sides of the presser foot. 15. The combination of stitch-forming means, means for causing relative movement between the stitch-forming means and a rigid heddle frame containing a series of heddles mounted to slide in the frame, the stitch-forming means being located in position to operate upon the middle portion of the heddles, means for selecting heddles singly and successively from the series, said selecting means operating near one end of the heddles, means engaging the middle portions of the heddles for feeding selected heddles past the stitch-forming means, and means for bringing the middle portion of each selected heddle into the range of action of said heddle-feeding means. 110
11. The combination of means for sewing together the eyes of heddles, means for selecting heddles from a group of unselected heddles, said selecting means operating near one end of the heddles, means for continuing to the sewing means the separation initiated by the selecting means, and means for controlling the eye of the separated heddle from the time it is released by the third mentioned means until it is engaged by the sewing means. 16. The combination of stitch-forming means, means for causing relative movement between the stitch-forming means and a rigid 120

- 130

5 heddle frame containing a series of heddles mounted to slide in the frame, the stitch-forming means being located in position to operate upon the middle portion of the heddles, means for selecting heddles singly and successively from the series, said selecting means operating near one end of the heddles, means engaging the eyes of selected heddles for feeding them past the stitch-forming 10 means, and means including a notched arm for bringing the eye of each selected heddle into the range of action of said heddle-feeding means, said arm being movable into engagement with a selected heddle adjacent to the selecting means and being thence movable longitudinally of the heddle to a position adjacent to the heddle-eye feeding means and being then movable out of engagement with the heddle and longitudinally into position 15 20 adjacent the selecting means.

17. A heddle feeding means comprising a support having a series of heddle receiving spaces therein, a feed member having a similar series of heddle receiving spaces, said 25 member being reciprocable transversely of the support to move a heddle into and out of the first mentioned spaces and being also reciprocable lengthwise of the support to place a heddle in register with successive spaces in 30 the support. 90

18. A heddle-feeding means comprising a support having a series of heddle-receiving spaces therein, a feed member having a similar series of heddle-receiving spaces, said 35 member being reciprocable transversely of the support to move a heddle into and out of the first mentioned spaces and being also reciprocable lengthwise of the support to place a heddle in register with successive 40 spaces in the support, and a yieldingly mounted presser foot against which the heddle is pressed by said feed member and along which the heddle is slidale in the lengthwise reciprocation of the feed member. 95

45 19. A heddle-feeding means comprising a support having a series of heddle-receiving spaces therein, a feed member having a similar series of heddle-receiving spaces, said member being reciprocable transversely of 50 the support to move a heddle into and out of the first mentioned spaces and being also reciprocable lengthwise of the support to place a heddle in register with successive spaces in the support, a pivoted arm, a second arm pivoted on the first arm, the second arm having two spaced fingers adapted to engage the heddle above and below the eye and above and below the feed member, said feed member and said arms being located at opposite sides of 55 the support, means for swinging the first arm to press said fingers against the heddle, a spring tending to swing the second arm into heddle-receiving position, and means for 60 swinging the first arm to withdraw said fingers from the heddle. 100

20. The combination of chain stitch-forming means including a work plate, a sewing needle, and a looper, said work plate having two parallel rows of heddle-eye-receiving spaces therein, a feed member reciprocable 70 longitudinally and transversely to advance a heddle-eye from one space to the next and thus to and past the needle, a yieldable presser foot, said presser foot and said feed member being located at opposite sides of the work plate, and a part secured to said feed member and provided with a tooth projecting through the work plate between said rows of spaces into position to enter a heddle eye, said presser foot having a yieldable section opposite said tooth. 80

In testimony whereof, I have hereunto affixed my signature.

HOWARD D. COLMAN. 85
